UNITED STATES PATENT OFFICE.

SAMUEL LYON, OF PULTNEYVILLE, NEW YORK.

PARING AND CORING MACHINE.

SPECIFICATION forming part of Letters Patent No. 409,111, dated August 13, 1889.

Application filed January 21, 1889. Serial No. 297,021. (No model.)

To all whom it may concern:

Be it known that I, SAMUEL LYON, of Pultneyville, county of Wayne, and State of New York, have invented certain new and useful 5 Improvements in Paring and Coring Machines; and I do hereby declare the following to be a full, clear, and exact description of the same, reference being had to the accompanying drawings, forming a part of this specification, and to the figures and letters of reference marked thereon.

My present invention relates to machines for paring and coring apples or other similar fruit, and particularly to that class employing a turn-table carrying a paring-knife adapted to revolve around the rotating fruit-fork, though some of the parts could as well be applied to other forms of machines; and it consists in certain novel features of parts, all as will be hereinafter fully described, and the novel features pointed out in the claims at the end of the specification.

In the drawings, Figure 1 is a front elevation of a machine constructed in accordance 25 with my invention ready for the paring operation; Fig. 2, a similar view showing the location of the parts just before the paring operation is finished; Fig. 3, a top plan view of Fig. 1; Fig. 4, a vertical sectional view 30 through the slide-operating mechanism when the operating-lever is in vertical position, moving the slide inward; Figs. 5 and 6, views of the coring device and slide-supports. Fig. 7, a rear view of the turn-table and knife-arm; Fig. 8, a side view of the same; Fig. 9, a view of the fruit-deflector, and Fig. 10 a view of a modification.

The main supporting-frame of the machine, constructed, preferably, of cast metal, is provided with laterally-extended supporting-feet 11, adapted to be secured to a suitable table or support, and between its two substantially upright end portions 22 are provided horizontal cross-bars 3, 4, and 5, the first mentioned at the bottom, the next 4 above it, and the last 5 constituting the top, and extending beyond the forward standard is an overhanging portion 16, on which the turn-table is supported, as will be described. This 45 frame is preferably formed in one piece, and in it are also formed half-bearings in which

operate the horizontal shaft 6 and the fork-shaft 7, held in place by bearing-plates 8, 8, bolted to the frame, as shown, the former shaft 6 being provided at one end with a large 55 gear 9, to which is attached an operating-handle 10, and at the other with a small bevel-pinion 11, meshing with the turn-table gear 12, supported in the overhanging portion of the main frame. 60

The fork-shaft 7, preferably of tubular form, is provided at its forward end with an ordinary fruit-fork 100 screwed upon it, and at its rear with a small pinion 14, meshing with gear 9, from which it receives motion, 65 and operating within this shaft is a doffer-rod 15, its end being adapted to project beyond the pinion 14 when the fruit is on the fork and to be moved inward by suitable devices when desired to eject the core. This 70 particular arrangement of core-doffer is not essential to the operation of the doffer-operating devices hereinafter described, but is a desirable form.

Secured to the lower portion of the main 75 frame is a flat bar or plate of metal 17, extending out some distance parallel with the fork-shaft, and to the outer end is secured a casting 18, forming a guide for the slide carrying the coring-tube and actuating the fruit-doffer. 80

19 represents a bracket carrying the coring-tube 20, mounted upon a bar or plate 21, preferably flat, operating in guides in the casting 18 and main frame, said plate constituting a 85 slide adapted to be reciprocated at suitable times to cause the coring-tube to pass over the fork and separate the fruit from the core.

The lower portion of casting 18 is provided with a slight recess 22 in one face fitting over 90 the bar 17, and a projecting portion 23, forming the bottom of the bearing for the bar 21. For the purpose of securing the casting to its support, and also of forming an adjustable bearing for bar 21, by means of which all lost 95 motion and wear of the parts can be taken up, I provide a plate 24, slotted at opposite ends, and having a shoulder 25 near its upper portion secured to the casting by bolts 26, 26, passing through the slots and entering the casting. The shoulder 25 bears on the top of the bar 21 and prevents all vertical move- 100

ment, while the plate and casting form its guides, the lower end of the plate projecting over bar 17 and securely clamping it to the casting. All wear can be readily taken up 5 by moving this plate down and securing it in position by means of the screws, and in order to prevent all liability of the plate becoming displaced during this adjustment, and to hold it securely in position I provide small lugs 27 10 27 on the casting, arranged to enter the slots, as will be understood.

The guide for the inner portion of the bar 21 is formed by a plate similar to plate 24, a support for said bar being formed by a depending arm secured thereto, and operating on a way, farther on described, and the lower end of plate 24 projects over bar 17, though this is not essential, as the latter is bolted to the frame near this point. The bracket 19 is 15 composed of two parts bolted to the bar 21, each part being provided with recesses, and grasping the tube between them, as shown, and above the tube each has a lug 28, the two forming a guide in which rests the fruit-dof- 20 fer rod 29, the outer end being adapted to strike against casting 18 when the slide is moved outward, and the inner end formed with or connected to a collar 30, sliding on the tube and adapted, when the rod is held sta- 25 tionary and the tube is moved, to push off the fruit.

For the purpose of delivering the pared fruit or the parings, or both, at either the front or the rear of the machine, I provide 30 an incline or chute 31, constructed, preferably, of sheet metal and having on its under side arms 32, preferably, also, of a single piece of sheet metal, and adapted, when in position, to clasp the sides of the bar 21 and hold the 35 chute directly beneath the end of the tube, so that as the fruit drops off it will be caused to pass in front or rear of the bar, as may be desired, depending on the direction in which it is inclined. It will be understood that this 40 chute can be reversed or removed entirely, if desired, the spring-arms grasping the slide facilitating this. As a means for operating this slide, though equally well adapted for moving any kind of a slide or carriage in a 45 machine of this general description, I prefer to construct the parts as follows: Mounted upon the main frame and secured to the upper and middle cross-bars is an upright bar or casting 33, having a stud or pin 35 project- 50 ing from its front, on which is mounted a large bevel gear-wheel 36, rotated in the direction of the arrow, Fig. 1, by a bevel-pinion 37 on the shaft 6. Near the lower end of this bar is provided a projection or boss 34, hav- 55 ing a reduced portion on its outer end, on which is pivoted a lever 39, the latter being held a sufficient distance in front of the gear 36 to permit its free operation. The upper end of this lever is provided with a slot 40, 60 in which operates a friction-roller 41, mounted on wrist-pin 42, formed upon or secured to the gear 36, the connection being such that

upon the rotation of the gear the lever will be vibrated on its pivot, and to the lower end is pivoted a cross-head 47, having slots 46 46 70 in its ends, as shown. To the inner end of the bar 21 is secured a depending arm 96, forming a support for the same, having at its lower end a flange or shoe 97, arranged to bear against the top and outer face of a plate 43 75 on the main frame, and on this arm are provided two pins 44 44, having friction-rollers 45 thereon, adapted to operate in the slots 46 in the cross-head. I prefer to support the inner end of the bar 21 upon the plate 43 through 80 arm 96, instead of directly underneath the plate 24 on the frame, as its bearing-points will be thus further removed from the fork, and the liability of gumming and unusual wear from the fruit-juice on a supporting- 85 surface will be lessened. The projection 25 on plate 24 bears on the top of the slide and holds it down on the way 43, and any wear at this point can be taken up by adjusting the said plate. When the gear 36 is rotated, 90 the pin 42 causes the lever 39 to be vibrated in opposite directions on its pivot, moving the slide through the parts just described, and it will be noted that in the rotation of gear 36 the pin 42 will operate in the lower portion 95 of the slot 40, near the pivot of the lever, when causing the outward movement of the slide, moving it quickly at this time, but as the outer end of the lever is acted upon when the slide is moved in the coring operation will 100 be accomplished more slowly, the point of connection being farther from the pivot.

In the operation of the slide by the cross-head 47, it will be noted, the latter is given a vertical movement, by reason of the end of lever 39 moving in the arc of a circle, thus insuring a more even motion with less liability of binding than would be the case were the end of the lever slotted to operate directly on the cross-bar 96, though this latter construction could be employed in some instances, if desired.

Pivoted to the main frame, or in the present instance to the end of bar 17, is a lever 48, its upper end being adapted at proper 115 times to operate upon the end of the core-doffer rod 15, and to it is pivoted a latch or link 49, its free end extending over the boss 38 on the bar 33, or a suitable projection on the main frame and normally supported there- 120 on, a hook or projection 50 being formed on its end to engage said boss 38 and prevent its moving too far to the right, and the lower side of the latch being further provided with a projection 51, preferably beveled slightly 125 on the left-hand side, with which engages a projection 52 on the bar 21 in the shape of a bracket secured to the cross-bar 96. When the doffer is projected to the right by impaling an apple on the fork, the doffer and its 130 lever are moved out, and the end of the link 49 is supported on the boss 38, and as the slide is moved to the right the projection 51 lifts the link and passes back of the projec-

tion 52; but when the slide moves in the opposite direction the projections 51 and 52 engage and the link and lever are carried with it, projecting the doffer-rod and removing the core from the fork. The link slides up on the boss 38 until the projections 51 and 52 are disengaged, when the doffer and lever can be returned to their first position by placing another apple on the fork, as will be understood.

10 The turn-table, supported in the overhanging portion 16 of the main frame, consists of a gear-wheel 12 (preferably recessed at 55 on its upper side and arranged to be rotated from pinion 11) upon a bolt or stud 56 on the frame. As a means for securing this bolt in position and facilitating the construction of the cam for operating the knife-arm, I cast the overhanging portion 16 with a half-bearing on its front side for the accommodation 15 of bolt 56 and a segmental flange 57 on its rear side, and provide a casting 59, bolted to the portion 16, having a recessed upper part for the bolt 56 and a lower flange 60, which latter, with the flange 57, constitutes the semi-circular cam for lifting the knife-arm over the fork-shaft when the turn-table is rotated. The head of the bolt 56 engages the under side of the gear-wheel 12, and the bolt is held in position by a nut 62 screwed on its upper 20 end, being prevented from rotation by a set-screw passing through casting 59 and engaging its side; or any other suitable device for the purpose could be employed, if desired.

25 The gear-wheel 12 is provided with a perforation 63 for the passage of the knife-arm 64, which latter is constructed with laterally-projecting arms or trunnions 65 65, having their bearings in recesses 66 66 in the upper side of plate 67, the latter being bolted to the 30 under side of the gear-wheel, said plate being further provided with a slot 68 for the knife-arm, the end of said slot serving as a stop for limiting its inward movement, caused by a spring 69, connected at one end to the knife-head 70 on the arm and at the other to a pin 71, secured in one of a series of perforations 72 in a flange 73 on the plate. The knife-head 70 is provided at its lower portion with a perforation for the parings, a paring-knife 74, and guard 75, as usual, and on its 35 rear side with a perforated lug 76, in which the end of the knife-arm projects, the upper portion partially encircling the arm and having a slot 77, through which passes a screw 78, the latter entering the arm and serving to limit the rotary motion of the head thereon: By connecting the spring 69 to the movable knife-head and providing a series of points of connection between the latter and the 40 knife-arm support the knife not only is held pressed against the fruit and the head permitted a slight independent oscillating motion, thus allowing it to follow more accurately the inequalities of the fruit-surface, but by changing the point of connection between the spring and turn-table and the direction of the pull of the spring, the angle at

which the knife strikes the fruit or leaves it can be changed, as may be desirable or necessary in order to pare the fruit at the ends in a more perfect manner, this adjustment depending upon the variety of fruit being operated upon.

45 The motion of the knife-arm toward the center of the turn-table, as stated, is normally limited by the end of the slot 68, and as a means for regulating this movement, so that if large fruit alone is to be pared the arm will be held farther from the fork, I in some instances employ a small wedge 79, secured to the arm by a screw 80, or otherwise, which, when in position, comes into contact with the end of slot 68, and may be moved up or down to determine the normal position of the knife relative to the fork, as shown in Fig. 10.

50 The bolt on which the turn-table rotates is preferably set at a slight angle to the plane of the fruit-fork, the center being preferably forward of the latter, as the knife only operates upon one side of the fruit when paring 40 and moves in a semicircle, being lifted over the fork-shaft and carried to the rear and away from the fork by the cam-surface, over which the end of the knife-arm moves.

55 When the machine is in the position indicated in Fig. 1, it is ready for operation, the slide carrying the coring-tube being at the extreme left and the knife-arm being swung back out of the way and against the tension of the spring, its upper end being confined under the cam 57 60. The operator now impales an apple upon the fruit-fork, pushing the doffer-rod 15 and its operating-lever out at the right, and then grasping the handle rotates the wheel 9, causing the rotation of the turn-table, the sliding of the coring-tube slide inward, and the rapid rotation of the fork-shaft.

60 As soon as the turn-table rotates sufficiently to release the upper end of the knife-arm from the cam its spring draws the knife down against the end of the fruit, which, being rotated rapidly, causes the skin to be removed, and the independent movement permitted the head allows it to follow the inequalities 115 of the fruit more readily. When a half-revolution of the turn-table has been made and the knife has reached the stem end of the fruit, the upper end of the knife-arm strikes the forward portion of the cam and turns the 120 arm on its pivots 65 65, raising the knife-head above the fork, and the continued movement of the turn-table carries the head around to the first position, being still held away from the fork by the cam. By thus holding the 125 knife-head away from the fork at all times, save during the paring operation, the operator is enabled to place the fruit on the fork without danger of his hand striking the knife.

65 During the paring operation the wheel 36 is of course being rotated from shaft 6, and the pin 42 causes the oscillation of the lever 39 and reciprocation of the coring-tube, which latter enters the fruit about the time the

knife is operating on the middle portion and severs the core just after the knife leaves the fruit. This inward motion of the tube, being caused by the operation of the pin 42 in the 5 upper end of the slot in lever 39, is consequently slow; but when the pin operates the opposite side of the slot to return the slide to outer position, as it is operating close to the pivot of the lever, it will move faster and 10 carry the slide outward rapidly. As the coring-tube slide is moving inward, the projection 52 on bar 21 slides up the incline on the latch 49, and, lifting the latter, becomes engaged with the projection 51. Then as the 15 carriage begins to move outward the latch is drawn with it, moving the core-doffer rod and causing the core to be pushed off the fork and into the coring-tube, the latch being released from the projection 52 at the proper time by 20 riding up on the projection on the frame—in the present instance formed by boss 38.

Just before the coring-slide reaches its outermost position the end of the fruit-doffer 29 strikes the casting 18, sliding the doffer-sleeve 25 outward and pushing the fruit which is supported on the tube off, when it is received upon the chute 31 and delivered at one side or the other of the machine, as may be desired.

30 When the machine resumes the position shown in Fig. 1 and another apple is placed upon the fork, the operation just described is repeated, and so on indefinitely.

The employment of the bar 17 and the casting 18 materially cheapens the cost and lightens the forward part of the machine, while the slide-bar 21, carrying the coring-tube, being guided in bearings at opposite ends, is steadied and its proper operation insured.

40 This machine is very simple in construction, is easily and cheaply made, and, as I have found in practice, is admirably adapted for the purpose, paring and coring the fruit without unnecessary waste.

45 I claim as my invention—

1. In a paring and coring machine, the combination, with the main frame, the turn-table carrying the paring-knife, the fork-shaft, gearing for connecting the turn-table and fork-shaft, and a wheel gearing with the fork-shaft 50 and provided with a projection, of the slide carrying the coring-tube, and a lever connected thereto pivoted on the frame and provided with a slot in which the projection on the gear operates to reciprocate said slide in opposite directions alternately, substantially as described.

2. The combination, with the slide, of the rotating gear having the wrist-pin, the pivoted lever having the slot in which the pin operates, and the cross-head mounted on the lever and connected to the slide by the slot-and-pin connection, substantially as described.

3. The combination, with the slide having 65 the two pins thereon, of the rotating gear having the wrist-pin, the pivoted lever having the slot in which the pin operates, and the

cross-head mounted on the lever and having the slots with which the pins on the slide co-operate, substantially as described.

4. The combination, with main frame, the slide-bar having the arm 96, and the guideway for the end of the latter, of the rotating gear having the pin, and the pivoted lever having the slot in which the pin operates connected to the slide, substantially as described.

5. The combination, with the main frame having the way 43, on which the slide operates, the bar secured to the frame, and the casting at the outer end of the latter having a projection thereon, of the slide and the adjustable plates 24, co-operating with the way on the main frame, and the projection on the casting forming guides for the slide, substantially as described.

6. The combination, with the main frame, the bar 17, connected thereto, and the casting at the end of the bar, having the projection, of the slide and the plate 24, secured to the casting, one portion co-operating with the projection on the casting to form a bearing for the slide and another clamping the bar 17 and casting together, substantially as described.

7. The combination, with the main frame, the bar 17, connected thereto, and the casting at the end of the bar having the projection, of the slide and the slotted plate 24, and screws for securing it to the casting, one portion co-operating with the projection on the casting to form a bearing for the slide and another projecting over and clamping the bar 17 and casting together, substantially as described.

8. The combination, with the slide, the bracket on the slide having the two lugs thereon, and the coring-tube attached to the bracket, of the fruit-doffer consisting of a rod and a sleeve encircling the tube, the doffer-rod resting between the lugs on the bracket, 110 a projection which the doffer-rod strikes to operate it, and the fruit-fork, substantially as described.

9. The combination, with the fruit-fork, the slide located below the fork, and a coring-tube located thereon, of the fruit-chute mounted on said slide, substantially as described.

10. The combination, with the fruit-fork, the slide, and a coring-tube located thereon, 120 of the fruit chute or incline having the depending arms adapted to embrace the said slide, substantially as described.

11. The combination, with the fruit-fork, the slide, and a coring device thereon, of the 125 fruit-chute having the arms adapted to removably engage the slide and hold the chute thereon in position to receive the fruit from the fork, substantially as described.

12. The combination, with the main frame, 130 the fruit-fork, and core-doffer rod operating between the tines of the fork, the pivoted lever operating the doffer, and the latch connected to the lever and having a projection

thereon, of the reciprocating slide having a projection for co-operating with the one on the latch, substantially as described.

13. The combination, with the main frame, 5 the fruit-fork, and core-doffer operating between the tines of the fork, the pivoted lever operating the doffer, and the latch connected thereto having a projection, of the reciprocating slide having a projection for co-operating with the one on the latch, and a projection on the main frame operating to lift the latch out of engagement with the slide, substantially as described.

14. The combination, with the turn-table, 15 the pivoted knife-arm, and the knife-head loosely mounted thereon, of a spring connected to the knife-head, and a series of points on the turn-table, to any of which the other end of the spring may be connected to vary 20 the angle of the knife relative to the arm, substantially as described.

15. The combination, with the main frame, the overhanging portion formed with the portion of the cam thereon, the co-operating casting forming the other part of the cam, the 25 bolt between said parts, and the turn-table mounted on the bolt, of the knife-arm pivoted on the turn-table and engaging the cam, and the fork-shaft, substantially as described.

16. The combination, with the fruit-fork, 30 the turn-table, and the knife-arm pivoted thereon, of the wedge secured upon the inner side of the arm and adapted to engage the turn-table and limit the inward movement of the knife-arm.

SAMUEL LYON.
